UNITED STATES PATENT OFFICE.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

PIPE-STILL FOR HIGH PRESSURE.

1,323,383.

Specification of Letters Patent. Patented Dec. 2, 1919.

Application filed May 8, 1916. Serial No. 96,260.

To all whom it may concern:

Be it known that I, FRANK E. WELLMAN, a citizen of the United States, residing at Kansas City, county of Wyandotte, State 5 of Kansas, have invented certain new and useful Improvements in Pipe-Stills for High Pressure, of which the following is a specification, reference being had therein to the accompanying drawing.

10 My invention relates to distilling apparatus, and especially to that employed in what is known as cracking hydrocarbons under high pressure and at a high temperature. It has for its object the production of a still 15 or retort which will not leak under any conditions of heat and pressure and variations thereof which are encountered in practice.

In my prior applications, Serial Nos. 32,704 and 69,500, I have disclosed a system 20 for the treatment of liquid hydrocarbons which includes with other elements, a superheater or high pressure still or retort consisting of straight lengths or sections of pipe laid parallel or at a small angle with each 25 other, and connected at their extremities by return bends. When the diameter of such pipes is increased beyond a certain point, it is difficult to form joints by the ordinary methods heretofore known by others, without 30 having leakage, especially after the joints have been exposed to temperatures of 750° F. and upward, and pressures of 600 pounds to the square inch and upward, which I employ in practice. In the course 35 of my work, I have found that such leakage is probably due to unequal expansion and contraction of the connected parts. This might be overcome theoretically by forming the entire structure of one continuous length

40 of pipe from end to end, but for reasons encountered in practice, and which are sufficiently obvious without being described in detail, the bending of a great length of pipe, especially of a large diameter, so as to reduce 45 it to a compact mass of straight parallel sections with relatively short return bends, is difficult if not impracticable. On the other hand, such a compact arrangement is necessary in order to make use of the economical 50 type of heating apparatus or furnace which I prefer to employ and which is set forth in my prior applications above referred to. Furthermore, it is very important to provide means for readily clearing 55 out deposits of carbon and other material

which accumulate in a retort of this kind in operation. The process of cracking and taking off the lighter series of hydrocarbons may be stated inversely as one involving the removal of the heavier series and carbon 60 from the liquid or vapor under treatment, and universal experience has shown that in such processes it is not always possible to completely drain off or carry away the heavier products, the carbon especially having 65 a tendency to accumulate in the heated portions of the system.

I solve the problems thus presented by building up my retort of sectional units, which will be shown and described herein as 70 straight parallel sections arranged in substantially the same figure as those in my prior applications, but united throughout so as to form a continuous, homogeneous and uniformly resistant structure throughout. 75 The manner of doing this, and the means of conjoining the several sections so as to produce the desired result, constitute the present invention.

After numerous experiments, I have 80 found that I can produce the desired conditions of uniformity and homogeneity, together with strength enough to resist high pressures, by welding all the joints, which I do, either by making a direct welded butt 85 joint, between the end of each straight pipe or section, and the registering end of a return bend on the next pipe, or by welding flanges on to the ends of the straight pipes and return bends, or by welding a bend on 90 each section to the side of the next adjacent section, and welding a flange on the end of the latter to receive a bolted cap which will permit of cleaning.

I have found that in this type of still or 95 retort which is exposed to uniform pressure transmitted through the liquid or vapor throughout its length, and to practically a uniform temperature, these welded joints have two very important advantages, viz., 100 (1) they expand and contract uniformly with the adjacent pipes, and (2) the metal can be readily thickened around the junction during welding, so that the actual resistance to tensile strains is greater than in 105 other parts of the pipe.

My invention is illustrated in the accompanying drawing, in which—

Figure 1 is a diagram showing a primary still or vaporizer, a compressor, and a pipe 110

still or retort with my invention applied to a few turns, typifying the many turns in a commercial still.

Fig. 2 is a detail view showing modifications, with flanges welded on the abutting ends of the straight pipe sections and the return bends.

Figs. 3 and 4 are respectively a plan view and an end view of superheater coils, the 10 furnace in Fig. 3 being in section on the line 3—3 of Fig. 4.

Referring to Fig. 1, as the vaporizer and the compressor with the connecting pipe lines, form no part of the present invention, 15 they need not be described, beyond stating that they are indicated by the numerals 1, 2 and 3 respectively.

The superheater or retort to which my invention is applied (although not confined 20 thereto), is indicated at 4 and may be substantially of the same type illustrated and described in my prior applications herein referred to. The coil or pipe-still is inclosed within a furnace with suitable means for 25 producing heat therein, and the coil is composed of a plurality of straight sections 5, connected by return bends 6. The welded joints are shown at 7, and are preferably made by the oxyacetylene process. The 30 joints shown in this Fig. 1, are simply butt-welds which may also be produced electrically if desired. Both these processes of welding are well known and in commercial use for other purposes, but so far as I know, 35 neither one of them has ever been employed for this purpose and with the results which I obtain. The pipe ends are prepared by mitering to gage, and are then placed together so as to register, put under pressure, 40 to hold them together, and the heat applied, with or without additional metal applied to the joint. The result is that the mitered edges flow and not only make a perfect weld, but thicken at the joints so as to increase 45 the resistance to tensile strain thereat. For an electrical weld, the edges are preferably prepared in a similar manner, and pressed firmly together while current at very low voltage is passed in large volume, so as to 50 raise the temperature of the edges to the welding point.

Instead of making a butt joint, it is also practicable to make a telescope or lap joint, but I do not consider this so desirable, because it is apt to produce an offset inside the tube. In making a welded coil of this type, the joints are of course permanent, which makes it impossible to remove the return bends for the purpose of cleaning out accumulations of carbon and other deposits after a run. Such deposits must therefore be removed by means of cleaning tools from the inlet and discharge ends of the pipe, indicated by the reference numerals 8 and 65 9, and to afford free passage for such tools,

it is desirable to have the interior of the pipe as smooth as possible.

In Fig. 2 I have shown a welded flanged joint, with one side solid and the other side in section. In this case the pipe 5 is preferably threaded into the ring or flange and welded at the points 11 and 14, inside and outside of the flange.

Other forms of welds, and methods of welding, may be employed, either in securing the flanges of Fig. 2, or for producing the butt-welds of Fig. 1. It will be understood that the illustration and description I furnish herein are intended for purposes of definition only, and not of limitation. I believe that it is novel and original with me to utilize welded joints in a high pressure pipe-still for the purpose stated, and I shall claim the same accordingly.

As an illustration of the advantages gained by this method of making joints, it should be observed that these coils are exposed to a temperature sufficient in course of time to change the granular structure of the steel or equivalent metal employed, and in order to restore the granular structure, it is necessary to heat the pipe above a certain critical point, say 1300° F. and then cool it very slowly. In the present case, I have found that my welded joints behave in the same manner as the straight pipe, this being due to the practically complete homogeneity of the metal throughout. Thus there is no danger of opening a joint at annealing temperatures, or having it warp or split on cooling. An incidental advantage lies in this, that if through accident or by reason of a defect in an original weld a joint should spring a leak, its continuity, homogeneity, and tensile resistance, may be fully restored by the same process of welding applied to the spot, without the necessity of removing the coil from the furnace.

In order to render this invention fully available, especially with bolted flanges which permit of ready removal of the return bends for cleaning purposes, it is necessary to carefully observe certain details of construction and arrangement which I have found in practice to be very important in their effect. Referring to Fig. 2 it will be observed that the flanges 12 and 13 are secured by edge or calk welding, that is to say by being first screwed upon the end of the pipe, and then welded around the edges 10, 11, 14 and 15. This particular weld is produced by softening the metal in the oxy-acetylene blast and at the same time feeding other melted metal into the joint. The result is an absolutely sealed threaded joint, in which several threads are integrally united, in addition to the extra metal used for the calk. The joint is of great strength, and therefore eminently fitted for its purpose.

After the flanges have been welded, the abutting faces of flanges and pipes are trued up by grinding or in any suitable machine, so that they will be fairly parallel when in position. I then place between them a pair of annularly corrugated copper gaskets 16, perforated to pass the bolts 17. These bolts extend through both flanges 12 and 13, and on their outer ends receive the nuts 18. The ends of the bolts, as indicated in Fig. 2, are very carefully cut off so as to leave a slight clearance, and in no case to extend outside the face of the nut. The reason for this is that when all the parts have been heated to the temperatures I employ, and then cooled down, the projecting ends of the fastening devices such as these bolts if any, are found to have extended over the faces of the nuts, so as to render it extremely difficult to remove the latter and separate the parts. To still further facilitate the operation of removal without in any wise detracting from the strength of the joint, I plate the threaded ends of the bolts and the threads of the nuts with a metal such as copper which prevents excessive adhesion, and is non-corrosive.

It will be understood that the apparatus herein described is not limited to use with hydrocarbon vapors, and while I do not herein claim any other specific form of pipe still than that described, my welded joints may be used with various other forms, as for example those in which some of the joints shown in Figs. 1 and 2 may be omitted. The number and relative arrangement of the joints are not essential features of the invention except as they are herein specifically claimed and I contemplate all such non-essential changes and modifications as may be fairly included within the scope of my claims.

Having thus described my invention, what I claim and desire to secure by Letters Patent of the United States is:

1. A joint for high pressure pipe stills or retorts comprising a pair of annular flanges or rings threaded and welded upon

adjacent pipe ends to form a homogeneous mass with their respective pipe ends, with means for mechanically and detachably securing said flanges together.

2. A joint for high pressure pipe stills or retorts comprising a pair of rings or annular flanges threaded and welded upon adjacent pipe ends, the outer faces of said flanges and the pipe ends being trued up, a compressible metal gasket interposed between the trued faces of the flanges, and bolts passing through the gaskets and securing the flanges together.

3. A joint for high pressure pipe stills or retorts comprising a pair of rings or annular flanges threaded and welded upon adjacent pipe ends, the outer faces of said flanges and the pipe ends being trued up, a compressible metal gasket interposed between the trued faces of the flanges, and bolts securing the flanges together, said bolts having nuts threaded upon their outer ends, and the bolts and nuts being so proportioned that when the nuts are screwed home to an extent necessary for holding, the ends of the bolts will lie within the plane of the outer faces of the nuts without any projection therefrom.

4. A joint for high pressure pipe stills or retorts comprising a pair of rings or annular flanges threaded and welded upon adjacent pipe ends, the outer faces of said flanges and the pipe ends being trued up, a compressible metal gasket interposed between the trued faces of the flanges, and bolts securing the flanges together, said bolts having securing devices such as nuts threaded upon their outer ends and the engaging surfaces of the bolts and securing devices being plated with a relatively soft and non-corrosive metal such as copper.

In testimony whereof I affix my signature in presence of two witnesses.

FRANK E. WELLMAN.
